COLLAPSIBLE STRUCTURE

Hiram A. Farrand, Berlin, N. H.

Original application March 16, 1939, Serial No. 262,324. Divided and this application October 23, 1941, Serial No. 416,255.

4 Claims. (Cl. 189—37)

This invention relates to a specific form of collapsible structure originally disclosed in my copending application Serial No. 262,324, filed March 16, 1939, of which the present application is a division.

The structure of the present case includes a longitudinally collapsible and extensible formation composed of two or more coilable, flexible, concavo-convex strips of longitudinally tapering character, maintained in the extended formation as a tubular structure, with the concave faces of the component strips facing inwardly toward the longitudinal axis of the extended structure by independent detachable encircling bands spaced apart longitudinally of the extended structure, as distinguished from the extended formations of the said copending application wherein the side edges of the component concavo-convex strips are parallel to each other and are maintained in extended formation by a system of interconnected brace elements.

The object of the present invention is to provide a collapsible structure of the type noted, wherein the confining bands will successively and automatically assume embracing positions separately, in spaced relation to each other longitudinally of the extended structure, as extension of the structure from a collapsed state progresses, and which will also completely and automatically detach themselves successively in reverse order from their embracing position to release the component strips for separation thereof, for independent storage, as collapse of the structure from an extended form progresses.

Another object of the invention is to provide automatic means for insuring firm embracing contact of the independent brace members about the component strips as the extension of the structure progresses.

In the accompanying drawings:

Fig. 1 is a perspective view of a fragmentary portion of the extended structure;

Figs. 2A and 2B constitute a side elevation of the collapsible structure and housing, with the latter shown in vertical sectional elevation;

Fig. 3 is a side elevation showing the structure collapsed and retracted into the housing;

Fig. 4 is a plan view showing the structure partially extended from the housing;

Fig. 5 is a transverse section taken on the line 5—5, Fig. 4, and

Figs. 6 and 7 illustrate a modification of the invention.

As shown in Figs. 1 to 5, inclusive, the collapsible structure 1 comprises a pair of flexible strips

2, 2, which are composed of spring material, preferably high-carbon steel ribbons, normally non-planar in their transverse direction. The opposite longitudinal edges of the strips 1, 1 are tapered or convergent. As shown in Figs. 2A and 4, the wide ends of the tapered strips lie within a vertical floor-stand or housing 10, and the small ends, forming the extremity of the projected structure, are joined together and to 5 a bracket 11, which latter is adapted to support, for example, a circular tray 12. As shown in the drawings, the two strips 2, 2 are similar in shape and size and lie, when extended, with their concave surfaces facing one another, i. e., 10 inwardly toward the longitudinal axis of the composite structure 1, with their smooth continuous edges 3, 3 in abutting relation throughout their lengths, thus forming the tapering tubular structure 1.

Surrounding the tapering tube 1 is a series of bands 5, 5 which are disposed at intervals along the length of the tube 1. Each band 5 is of such shape and dimensions as to closely fit the tube 1 at its particular location therealong, thereby 15 holding the two strips 2, 2 in a tight embrace. Thus, the entire structure, as extended, forms one whole composite arm, strut or cantilever-beam, which supports the tray or any other desired appliance, etc., at its extreme end.

Obviously, the opening 4 in each ring differs in size from all the other rings and fits the tube 1 only at its own particular place along the length of the tubular formation. As will be seen by 20 referring to Figs. 2A—2B, the extended portions of strips 2, 2 may constitute only a fractional part of the total respective lengths of the strips 2, 2, and a further portion of each strip may be stored within the hollow interior of the vertical floor-stand or housing 10, where such unextended

25 portions remain in readiness to move out to pick up and form, with other successive rings 5, 5 an additional length of the composite arm.

40 The unused rings 5, 5 are stacked in readiness in front of a head plate 13 of the housing 10 to join and embrace the strips 5, 5 with which they move out in succession, each being carried forward when its particular point on the tapered tube 1 becomes wedged within its embrace.

45 The conical formation of the assemblage of detached rings or bands 5, 5 in front of head plate 13, is the result of the progressive dimensional relationship of the openings 4, 4 of the rings. Each ring is of such a size in relation to its neighbors that it cannot pass through the orifice 4 of its next larger neighbor and the larg-

est of the series cannot pass through the orifice 14 in the plate 13 through which the strips 2, 2 move longitudinally as the structure 1 is extended or retracted relative to the housing 10. Consequently, the entire series of unused rings 5, 5 lie stacked in front of plate 13 in readiness to be carried out, seriatim, as the tubular formation 1, passing within their respective openings 4, progresses outwardly. Each ring thus follows the one preceding it at a prearranged distance therefrom.

In Fig. 3, the entire composite structure 1 is shown as withdrawn and the parts stored, all the rings 5, 5, being stacked in front of plate 13, and the strips 2, 2 lying within the hollow of the floor-stand or housing 10.

To prevent all but the outermost proper ring 5 from moving forward prematurely with the movement of the strips 2, 2, a retarding device has been provided. In Fig. 3, two bars or rollers 15, 15 are shown reposing, one above and the other below the tube 1, immediately in front of the outermost ring 5 of those stacked in front of plate 13. These rollers are held in positions parallel to one another and pressed upon the tubular structure 1 by springs 16, 16, which are attached to extensions 17, 17 (Fig. 5) of tie bars 18, 18. The end shafts of the rollers 15, 15 are held in bearings 19, 19 of the enlarged and squared ends of rods 20, 20.

The rods 20, 20 extend back through holes in a plate 21 secured to the housing 10. Behind this anchor plate 21 the rods 20, 20 are held under tension by compressive springs 22, 22 which press outwardly upon the rod-end collars 23, 23.

The position of the rollers 15, 15 with respect to the foremost ring 5 of the stack is maintained by reason of the relative strengths of the two sets of springs 22, 22 and 16, 16. This relativity is such that the combined efforts of the springs retain the outermost ring 5 firmly in front of the stack until sufficient force is applied thereto by outward axial movement of the tubular formation 1 to draw the outer ring 5 forward, and which can take place only after the strips 2, 2 have been tightly gripped and held together by the outermost ring 5.

As each successive ring 5 is drawn forward from between the rollers 15, 15, by forcing them apart, the springs 16, 16 close in behind the departing ring 5 while the springs 22, 22 draw the rollers 15, 15 back against the succeeding ring 5 of the stack, holding it firmly in position until it, too, is drawn forward by reason of its embrace of the strips 2, 2.

All that is necessary to reverse the process and collapse the structure is to exert an axial push upon the outer end of the composite structure 1, whereupon the strips 2, 2 will be pushed back axially into the interior of the housing 10. Each ring 5, in following the progress of the strips, will force its way between rollers 15, 15 and stop when it becomes blocked by the preceding ring 5 between it and plate 13. Due to the relative strengths of the springs 16, 16 and 22, 22, the rollers 15, 15 move down and forward in front of the last ring 5 to enter the stack and retain the collection in compact formation.

It will be observed that the housing 10 is provided with a swivel joint 24, which adds to the usefulness of the device by permitting the adjustable arm, composed of the structure 1 and head 10a of the housing 10, to swing in a complete circle.

As shown in Fig. 2A, the inner, wider portions 2a, 2a of the strips 2, 2, may hang freely within the upright pedestal portion 10b of the housing 10, or the housing may be provided with suitable means for coiling the strips 2, 2 separately as disclosed in the parent application previously noted.

Furthermore, instead of the composite arm 1 extending laterally from the pedestal or housing 10, it may project vertically therefrom in axial alignment therewith, in the same general manner as disclosed in said parent application, without departing from the spirit of the invention.

Furthermore, instead of the embracing bands passing completely around the assembled component concavo-convex strips which form the body of the structure, as shown in Figs. 1 to 5, inclusive, the encircling or embracing bands 5a and 5b shown in Figs. 6 and 7, respectively, are discontinuous. As shown in Fig. 6, the band 5a embraces the full cross-section of the concavo-convex strip 2a, and is provided with end portions 25a, 25a, which embrace the marginal portions of the opposite concavo-convex strip 2b, leaving a gap 26a between said ends. The next successive band 5b, as shown in Fig. 7, embraces the full width of the concavo-convex strip 2b and its end portions 25b, 25b embrace the marginal portions of the strip 2b, with a gap 26b therebetween.

Preferably the discontinuous bands 5a and 5b alternate along the length of the extended portion of the structure. If desired, continuous bands 5 may be interspersed with the discontinuous bands 5a, 5b and vice versa.

I claim:

1. A collapsible and extensible structure including a housing structure, a longitudinally-tapering composite structure comprising a plurality of longitudinally-tapering resilient strips normally of non-planar cross-section arranged in laterally-adjacent relation about the longitudinal axis of the structure and collectively forming the main body of the structure with a uniform cross-sectional contour of constantly changing dimensions along the length of said body, each strip being imperforate and smooth edged throughout that portion thereof which is adapted to constitute a component of the main body of the structure, a series of separate disconnected bands embracing said body at spaced intervals along its length, said bands being respectively provided with central openings of similar contours differently dimensioned in accordance with the variations in the cross-sectional dimensions of said body at the places respectively embraced by said bands individually the progressively increasing cross-sectional area of the tapering main body as formed by said strips producing a wedging of said body within each of said separate bands successively and rigidly securing said strips together at each of said embracing intervals for rigidifying said structure, and means for jamming said bands into rigidly-embracing contact consecutively with said strips as said strips are progressively projected concurrently from said housing structure.

2. A collapsible and extensible structure including a housing structure, a longitudinally-tapering composite structure comprising a plurality of longitudinally-tapering resilient strips normally of non-planar cross section arranged in laterally-adjacent relation about the longitudinal axis of the structure and collectively forming the main body of the structure with a uniform cross-sectional contour of constantly

changing dimensions along the length of said body, each strip being imperforate and smooth edged throughout that portion thereof which is adapted to constitute a component of the main body of the structure, a series of separate disconnected bands embracing said body at spaced intervals along its length, said bands being respectively provided with central openings of similar contours differently dimensioned in accordance with the variations in the cross-sectional dimensions of said body at the places respectively embraced by said bands individually the progressively increasing cross-sectional area of the tapering main body as formed by said strips producing a wedging of said body within each of said separate bands successively and rigidly securing said strips together at each of said embracing intervals for rigidifying said structure, means for jamming said bands into rigidly-embracing contact consecutively with said strips as said strips are progressively projected concurrently from said housing structure, and means for disengaging said bands from said strips consecutively in reverse order as said strips are concurrently moved in an opposite direction into said housing.

3. A collapsible and extensible structure including a housing structure, a longitudinally-tapering composite structure comprising a plurality of longitudinally-tapering resilient strips normally of non-planar cross-section arranged in laterally-adjacent relation about the longitudinal axis of the structure and collectively forming the main body of the structure with a uniform cross-sectional contour of constantly changing dimensions along the length of said body, each strip being imperforate and smooth edged throughout that portion thereof which is adapted to constitute a component of the main body of the structure, a series of separate disconnected bands embracing said body at spaced intervals along its length, said bands being respectively provided with central openings of similar contours differently dimensioned in accordance with the variations in the cross-sectional dimensions of said body at the places respectively embraced by said bands individually the progressively increasing cross-sectional area of the tapering main body as formed by said strips producing a

wedging of said body within each of said separate bands successively and rigidly securing said strips together at each of said embracing intervals for rigidifying said structure, means for jamming said bands into rigidly-embracing contact consecutively with said strips as said strips are progressively projected concurrently from said housing structure, and means for disengaging said bands from said strips consecutively in reverse order as said strips are concurrently moved in an opposite direction into said housing, said housing comprising a stationary hollow base portion for receiving said strips as said composite structure is collapsed.

4. A collapsible and extensible structure including a housing structure, a longitudinally-tapering composite structure comprising a plurality of longitudinally-tapering resilient strips normally of non-planar cross-section arranged in laterally-adjacent relation about the longitudinal axis of the structure and collectively forming the main body of the structure with a uniform cross-sectional contour of constantly changing dimensions along the length of said body, each strip being imperforate and smooth edged throughout that portion thereof which is adapted to constitute a component of the main body of the structure, a series of separate bands embracing said body at spaced intervals along its length, said bands being respectively provided with central openings of similar contours differently dimensioned in accordance with the variations in the cross-sectional dimensions of said body at the places respectively embraced by said bands individually, means for jamming said bands into rigidly-embracing contact consecutively with said strips as said strips are progressively projected concurrently from said housing structure, means for disengaging said bands from said strips consecutively in reverse order as said strips are concurrently moved in an opposite direction into said housing, said housing comprising a stationary hollow base portion for receiving said strips as said composite structure is collapsed, and a head portion pivotally mounted on said base portion and supporting said jamming and disengaging means.

HIRAM A. FARRAND.
